US00D560809S

(12) **United States Design Patent** (10) **Patent No.:** **US D560,809 S**
(45) **Date of Patent:** **** Jan. 29, 2008**

(54) **ELECTRODE ARRAY**

(75) Inventors: **Elvir Causevic**, St. Louis, MO (US);
Christian Christiansen, Chesterfield, MO (US); **Daniel Metzger**, Belleville, IL (US); **Greg Holderfield**, Oak Park, IL (US); **Elliott Hsu**, Raleigh, NC (US)

(73) Assignee: **Everest Biomedical Instruments**, Chesterfield, MO (US)

(**) Term: **14 Years**

(21) Appl. No.: **29/238,840**

(22) Filed: **Sep. 22, 2005**

(51) **LOC (8) Cl.** **24-01**

(52) **U.S. Cl.** **D24/187**

(58) **Field of Classification Search** **D24/168, D24/187, 200, 206-207, 215; D2/878; 600/109, 600/139, 383; 607/54, 59, 60, 62, 72-74**

See application file for complete search history.

(57) **CLAIM**

The ornamental design for an electrode array, as shown and described.

DESCRIPTION

FIG. 1, is a perspective side view of the electrode array showing our new design. The electrical coupling cable and the head of the human subject, are shown in broken lines, and form no part of the claimed design;

FIG. 2, is a top view thereof;

FIG. 3, is a bottom view thereof;

FIG. 4, is a front view with the back view being a mirror image thereof;

FIG. 5, is a left side view thereof; and,

FIG. 6 is a right side thereof.

The broken line showing of the electrical coupling cable and the head of the human subject is included for illustrative purposes only and forms no part of the claimed design.
